UNITED STATES PATENT OFFICE.

FREDERICK W. PFEIFER, OF ST. LOUIS, MISSOURI.

FOLDING COT AND STRETCHER.

1,350,516.

Specification of Letters Patent. Patented Aug. 24, 1920.

Application filed September 13, 1918. Serial No. 253,944.

To all whom it may concern:

Be it known that I, FREDERICK W. PFEIFER, a citizen of the United States, residing at St. Louis, State of Missouri, have invented 5 certain new and useful Improvements in Folding Cots and Stretchers; and I do hereby declare the following to be a full, clear, and exact description of the invention, such as will enable others skilled in the art to 10 which it appertains to make and use the same.

This invention relates to new and useful improvements in cots, and particularly to folding cots.

15 One object of the present invention is to provide a cot which may be easily and quickly folded into a small and compact condition so as to occupy the smallest amount of space and which is especially adapted for 20 military and camp uses.

Another object is to provide a novel and improved device of this character wherein the cot is readily capable of being converted into a stretcher for use in emergencies.

25 A further object is to provide a novel and improved device of this character wherein the canvas bottom of the cot is held so that it may be readily removed for repairs or substitution, and which will easily fold when 30 the cot is telescoped or collapsed.

In the drawing:

Figure 1 is a side elevation of a cot made in accordance with my invention.

Fig. 2 is an enlarged top plan of one end 35 portion of the cot.

Fig. 3 is an enlarged top plan view of one end portion of the cot showing the supporting legs in the position assumed when the cot is used as a stretcher.

40 Fig. 4 is an enlarged vertical transverse sectional view taken on the line 4—4 of Fig. 2.

Fig. 5 is an enlarged sectional view taken on the line 5—5 of Fig. 2.

45 Fig. 6 is an enlarged sectional view taken on the line 6—6 of Fig. 2.

Referring particularly to the accompanying drawing, 10 represents a pair of parallel tubular side rail sections each of which is 50 formed with a longitudinal slot 11 in the upper side thereof, the inner wall of each slot having a recess or notch 12 adjacent the head end thereof. Telescoped into each of the sections 10 is a slightly smaller tubular section 13, said section having a longitudinal slot 14 in the upper side thereof which

registers with the slot of the appropriate section 10 into which it is telescoped. In the lower side of each of the sections 10 there is formed a longitudinal slot 15 through which 60 projects a stud bolt 16 carried by the lower side of the section 13, winged nuts 17 being engaged on said bolts to hold the telescoping sections in different adjusted positions.

A canvas bottom 18 has its longer marginal edges formed with the tubular pockets 19 which are disposed longitudinally in the sections 10 and 13, the body of the bottom leading thence through the slots thereof. Disposed longitudinally within each of the 70 pockets is a rod 20, said rod being formed of two sections hinged together at 21, for a purpose which will presently appear. One end of the rod is formed with an upturned portion 22, which is provided with a head 75 23 and arranged for engagement in one of the before-mentioned notches 12, being drawn into the same by tension on the bed bottom. Carried by the inner face of the outer end of each of the rail sections is a lug 24, and pivotally mounted on each lug is a leg member 25. The legs at each end of the cot are crossed and pivotally connected, as shown at 26. Pivotally mounted adjacent each of the lugs 24 is a sectional adjustable brace 27 the other 80 end of which is pivotally connected to a leg member 25. Loosely pivoted to the inner portion of the outer end of each of the rail sections is a longitudinally slotted brace link section 28, said sections being connected by 85 the bolts 29, and held against slipping with respect to each other by the corrugations 30 on the abutting faces thereof.

From the foregoing description, and from the accompanying drawing, it will be seen 95 that the legs of the cot are capable of swinging movement on their pivots into the position shown in Fig. 3, the braces 27 being extended to permit such movement. The cot is thus converted into a stretcher which can 100 be placed on the ground, floor, or bed, as the circumstances warrant, the outer ends of the legs being adapted to serve as handles by which the stretcher is carried.

In normal extended condition the up- 105 turned ends of the rods 20 are disposed in the notches 12, whereby the fabric bottom covers the braces and legs at the adjacent end of the cot. When the cot is to be packed, the sections 13 are slipped into the sections 110 10 until the joints 21 appear at the outer ends of the sections 13. The rods are then

folded over onto the telescoped sections, together with the folded fabric bottom, which is carried by the rods. The upturned ends of the rods 20 are only removed from the notches 12 when the entire fabric bottom is removed for repairs or replacement, and this can easily be accomplished by forcibly withdrawing said ends out the extremities of the slots 11—possibly spreading the end of the side rail 10 a little to permit such withdrawal.

There is thus provided a novel and efficient device which is readily and conveniently convertible from a cot to a stretcher, as the occasion requires. Furthermore, the device is readily capable of being placed in a small and compact condition for packing or transportation.

Attention is particularly called to the legs 20 which are adapted to support the device as a cot, and to serve as handles when the device is used as a stretcher.

What is claimed is:

In a structure of the class described, the combination with side rails each made up of outer and inner tubular telescopic sections

having aligned slots in their upper sides and the outer section having a longitudinal slot in its lower side, a stud bolt projecting from the inner section through the last-named slot 30 and receiving a nut for holding the sections relatively adjusted, and folding legs for supporting said rails and braces for holding them separated when so supported; of a flexible bottom connecting said rails and 35 passing downward through their upper slots, its edges having longitudinal tubular pockets, in each pocket a rod made in sections, a hinge connecting the sections end to end at a point to be exposed when said tubular sections are telescoped together whereby one rod section and the bottom thereon can be folded over onto the other section, and connections between the remote end of the other rod section and the larger tubular 45 section.

In testimony whereof, I affix my signature, in the presence of two witnesses.

FREDERICK W. PFEIFER.
